UNITED STATES PATENT OFFICE.

JOHN F. STANDISH, OF WINTHROP, MASSACHUSETTS, ASSIGNEE, BY MESNE ASSIGNMENTS, TO UNITED-XPEDITE FINISHING COMPANY, OF BERWICK, MAINE, A CORPORATION OF MAINE.

HEATING DEVICE.

1,320,653.

Specification of Letters Patent.

Patented Nov. 4, 1919.

Application filed October 9, 1917. Serial No. 195,614.

To all whom it may concern:

Be it known that I, JOHN F. STANDISH, a citizen of the United States, residing at Winthrop, in the county of Suffolk and State of Massachusetts, have invented certain Improvements in Heating Devices, of which the following description, in connection with the accompanying drawings, is a specification, like reference characters on the drawings indicating like parts in the several figures.

This invention relates to means for heating various substances, and especially to means for maintaining in a fluid condition waxes, cements and other materials employed in connection with shoemaking. Factories to which are furnished machines using these materials in their operations are often equipped with only one heat-generating agency. For example, a particular factory which is to be supplied with a burnishing machine provided with a receptacle for heating wax may have gas installed and no electricity, while in another factory the opposite condition may exist.

An object of my invention is to provide a device adapted to be heated by different agencies to meet different conditions encountered. For this purpose a receptacle for the material to be heated is arranged to effectively coöperate with heating devices of different character, as gas burners or electric heating units.

A further object of the invention is to so arrange the receptacle that any one of the plurality of types of heating devices may be readily applied to it.

When one of the devices exerts its heating effect by combustion, an object of the invention is to cause a passage to which the heating devices may be applied to serve as a flue for the combustion-heating device when the companion device is removed.

Still another object of the invention is to heat in an efficient manner a material-feeding member. This may be accomplished by having this feeding member move over

a surface upon a portion of the receptacle to which heat is applied to affect the contained material.

An apparatus for attaining the objects mentioned and related objects is hereinafter described and illustrated in the annexed drawings, in which,

Figure 1 is a central vertical section through one embodiment of the invention, and

Fig. 2 is a side elevation of the receptacle, parts being broken away.

I have chosen as a form representative of the invention the wax pot of a burnishing machine, this including a receptacle 10 having a bottom wall 12 and a side wall 14 and central portion 16 rising from 12. Between the outer wall and inner portion is an intermediate space to contain the wax W to be heated. A wheel 18 for applying this to the burnishing member of the machine is rotatably mounted upon the portion 16, it contacting over a considerable area of its inner side with a plane surface 19 thereon. The wheel is driven in any convenient manner. Through the receptacle is a heating passage or chamber for coöoperating with different types of heating devices. One portion of the passage is situated beneath the bottom wall 12, being furnished by a recess 20 the bottom of which may be closed by a base plate 22 upon which the receptacle is supported, it being secured in place by screws 24. The recess is open at one side, as shown at 26, and above this opening is a curved shield 27 to protect the elements coöperating with the opening from wax which may drip from the top of the pot.

Opening from the recess 20 is an upwardly extending passage 28 preferably located at the axis of the receptacle and at the center of the portion 16. This passage 28 is of such form as to receive an electric heating unit 30, which may be of any desired construction having the capacity necessary to generate the heat required. The unit when in place in the passage 28 preferably ex-

tends from the bottom thereof to a point above the level of the wax in the receptacle. In assembling the electric unit and receptacle, the latter is removed from the base 5 and the unit introduced through the top of the passage 28, the leading-in wires 34 of the unit projecting into the recess 20. The top of the passage 28 is threaded to receive a plug 32, serving to prevent wax 10 which might short circuit the unit from entering the passage and also preventing the escape of the heat generated. Before the receptacle is attached to the base, the leading-in wires are connected to the terminals 15 36 of one section of a push plug or other suitable electrical connector, the insulating block 37 of which is fixed to the under side of the bottom wall of the receptacle by a screw 38. The other section 40 of the plug 20 is mounted within a holder 42, being secured in place therein by a screw 44. To the terminals of this second section are joined the supply conductors 46 which may be encircled by a spiral spring protector 48 25 carried by the end of the holder. The heat generated by the current flowing through the unit 30 is directly communicated to the wax through the wall of the portion 16. It will be noted that the leading-in conductors 30 of the unit are so situated that they can not be short circuited or injured otherwise, and that the connecting means is protected against the drip of wax from the pot by the shield 27.

35 If gas rather than electricity is to be used as a heating agent, instead of placing the electric unit with its supporting and connecting means in the passages of the receptacle, a burner 50, which may be of the Bunsen type, may be mounted upon a convenient portion of the frame of the machine at 52. The delivery opening of this burner is situated in proximity to the opening 26 of the portion 20 of the passage, and when the gas 40 is lighted it delivers its flame within the passage 20, the heat therefrom rising through the passage 28 which serves as a flue, the plug 32 being removed. Therefore the heat of the flame is delivered to the material both through the bottom wall 12 and through the wall of the portion 16. With this arrangement of the device, the shield 45 50 55 27 prevents the dripping wax from being ignited by the flame, deflecting it to opposite sides of the opening 26. Whatever agent is employed, its heat is directly communicated to the feed wheel 18 through the surface 19, so that this wheel is at a temperature sufficient to maintain the material fluid as it is applied.

It will be clear that not only may either of the different heating devices be readily applied to the receptacle and will coöperate

therewith in a highly efficient manner, but that if it is desired to change the heating agent, this may easily be accomplished by one not possessing special skill. 65

Having thus described my invention, what I claim as new and desire to secure by Letters Patent of the United States is:

70 1. A device for heating material comprising a receptacle for the material to be heated provided with a passage having different portions respectively constructed and arranged to coöperate with heating devices of different character.

75 2. A device for heating material comprising a receptacle for the material to be heated provided with a passage having different portions respectively constructed and arranged to coöperate with heating devices of different character, one of the portions of the passage conducting through the receptacle the heat generated in the other portion.

80 3. A device for heating material comprising a receptacle for material to be heated provided with a passage having different portions, one of said portions being constructed and arranged to receive a heating device of one character and the other portion being arranged to coöperate with a heating device of a different character on the removal of the first-mentioned heating device. 85 90

95 4. A device for heating material comprising a receptacle for the material to be heated provided with a passage having different portions, one of said portions being constructed and arranged to receive an electric heating device and the other portion being arranged to coöperate with a device heating by combustion.

100 105 5. A device for heating material comprising a receptacle for the material to be heated provided with a passage situated in its lower portion to receive a heating device and an upwardly extending passage leading therefrom for another heating device.

110 6. A device for heating material comprising a receptacle for the material to be heated provided with a passage constructed and arranged to receive a plurality of heating devices, one of which operates by combustion, the passage when the combustion-heating device is in use and the companion device is removed serving as a flue for the former.

115 120 7. A device for heating material comprising a receptacle for the material to be heated provided with a passage constructed and arranged to receive an electrical heating device and a device for heating by combustion, the passage when the electrical heating device is removed therefrom and the combustion-heating device is in use serving as a flue for the latter.

125 8. A device for heating material comprising

- ing a receptacle for the material to be heated provided with a passage having different portions, one of said portions being constructed and arranged to receive an electric heating device and the other portion being arranged to coöperate with a device heating by combustion, the first-named portion of the passage, when the combustion-heating device is in use, serving as a flue therefor. 5
- 10 9. A device for heating material comprising a receptacle for the material to be heated provided with a passage having different portions respectively constructed and arranged to coöperate with heating devices of different character, and means for closing one end of the passage. 15
10. A device for heating material comprising a receptacle for the material to be heated provided with a passage situated in its lower portion to receive a heating device and an upwardly extending passage leading therefrom for another heating device, and means for closing the upper end of the upwardly extending passage. 20
- 25 11. A device for heating material comprising a receptacle having side and bottom walls and an inner portion rising through the receptacle from the bottom wall, there being a recess in the receptacle beneath the bottom wall and a passage through the inner portion connecting with the recess. 30
- 35 12. A device for heating material comprising a receptacle having side and bottom walls and an inner portion rising through the receptacle from the bottom wall, there being a recess in the receptacle beneath the bottom wall and a passage through the inner portion connecting with the recess, and a plug for coöperation with the upper 40 end of the passage. 45
13. A device for heating material comprising a receptacle having side and bottom walls and an inner portion rising through the receptacle from the bottom wall, there being a recess with an opening at one side of the receptacle beneath the bottom wall and a passage through the inner portion connecting with the recess. 50
- 55 14. A device for heating material comprising a receptacle having side and bottom walls and an inner portion rising through the receptacle from the bottom wall, there being a recess with an opening at one side of the receptacle beneath the bottom wall and a passage through the inner portion connecting with the recess, and means situated adjacent to the recess for securing a heating device. 60
15. A device for heating material comprising a receptacle having side and bottom walls and an inner portion rising through the receptacle from the bottom wall, there being a recess with an opening at one side of the receptacle beneath the bottom wall and a passage through the inner portion connecting with the recess, and means situated adjacent to the recess for securing a heating device. 65
- of the receptacle beneath the bottom wall and a passage through the inner portion connecting with the recess, and a shield situated above the opening to the recess. 70
16. A device for heating material comprising a base plate, a receptacle removably secured to the base plate and having a recess forming with the base plate a passage opening at the side of the receptacle, there being a passage leading from that first named through the receptacle, and a heating device coöperating with one of the passages. 75
17. A device for heating material comprising a base plate, a receptacle removably secured to the base plate and having a recess forming with the base plate a passage opening at the side of the receptacle, there being a passage leading from that first-named through the receptacle, a heating device coöperating with the passage through the receptacle, and connections for the heating device entering the recess. 80
- 85 18. A device for heating material comprising a receptacle for the material to be heated provided with a passage situated at its lower portion and an upwardly extending passage leading therefrom, and a heating device coöperating with one of the passages. 90
- 95 19. A device for heating material comprising a receptacle for the material to be heated provided with a passage situated at its lower portion and an upwardly extending passage leading therefrom, a heating device coöperating with one of the passages, and connections for the heating device entering the other passage. 100
- 105 20. A device for heating material comprising a receptacle for the material to be heated provided with a passage situated at its lower portion and an upwardly extending passage leading therefrom, an electrical heating device situated in the upwardly extending passage, and connections for said heating device entering the lower passage. 110
- 115 21. A device for heating material comprising a receptacle having a portion extending through the material for communicating heat thereto, means for heating said portion, and a material-feeding member mounted upon the heated portion to receive heat therefrom and transmit it to the material. 120
- 125 22. A device for heating material comprising a receptacle having a central portion forming with the receptacle an intermediate material-receiving space, means for heating said portion and a feeding member mounted upon the central portion to receive heat therefrom and extending into the space, said member transmitting heat to the material it carries and that within the space. 125
23. A device for heating material com-

prising a receptacle having a portion extending through the material for communicating heat thereto, means for heating said portion, and a material-feeding member provided with a face movable in contact with the heated portion to conduct heat directly through the member to the material on said member.

24. A device for heating material comprising a receptacle having a portion extending through the material to communicate

heat thereto and being provided with a plane surface, means for heating said portions, and a feeding wheel contacting with said surface over a considerable area of one of its 15 sides to effectively conduct heat from the heated portions through the contacting surfaces to the material on the wheel.

In testimony whereof I have signed my name to this specification.

JOHN F. STANDISH.
